UNITED STATES PATENT OFFICE.

HUGO BOLDT, OF DURANT, IOWA.

ROOF-GUTTER BRACKET.

1,170,869.

Specification of Letters Patent.

Patented Feb. 8, 1916.

Application filed April 29, 1915. Serial No. 24,746.

To all whom it may concern:

Be it known that I, HUGO BOLDT, a citizen of the United States, residing at Durant, in the county of Cedar and State of Iowa, have invented certain new and useful Improvements in Roof-Gutter Brackets; and I do declare the following to be a full, clear, and exact description of the invention, such as will enable others skilled in the art to which it appertains to make and use the same.

My invention relates to roof gutter brackets, and has for its object to provide a device of this class which although being of extremely simple and inexpensive construction, will be highly efficient and durable in operation.

With this object in view, the invention resides in the specific construction herein-after described and claimed and shown in the accompanying drawings wherein like reference characters designate corresponding parts throughout the several views and wherein:

Figure 1 is a perspective view of a portion of a roof showing the application of a number of the improved brackets to the beaded gutter thereof; Fig. 2 is a vertical section through a portion of the gutter and the roof showing one of the brackets in edge view; and, Fig. 3 is a perspective view of one of the brackets.

In this drawing which constitutes part of the application, R designates a portion of an inclined roof constructed of shingles S or the like. Near the lower edge of the roof R, the gutter G is provided, said gutter including an inclined base plate P which is shown in the present application as inserted beneath one of the lower rows of shingles, while extended upwardly from the lower edge of the plate P, is an additional plate whose upper edge is curled outwardly and then inwardly to provide the bead B. It is from the bead B to the lower edge of the roof R that the several braces 1 extend, whereby to not only effectively brace the upwardly extending plate of the gutter, but to present a rather attractive appearance.

Each bracket 1 is formed of a flat rigid strap or bar 2 disposed at a suitable incline and having its lower end bent laterally to provide an attaching foot 3 having an opening 4 through which a nail or the like may be passed to secure said bracket to the roof. The upper end of the strap 2, however, is

bent into the form of an S as indicated at 5, one arm 6 of one of the loops 7 of the S being extended laterally from the upper end of the strap 2, while the remainder of the loop 7 and the other loop 8 integrally joined thereto continue endwise from said upper end of the strap. It is to be observed that the loop 8 is of greater size than the loop 7 and that said loop 8 receives therein the bead B, its free end 9 contacting with the upper side of the bead, while the loop 7 abuts the lower side thereof and provides a rigid shoulder against which the same bears. When the parts are disposed in this manner, it will be observed that the loop 8 contacts with the upright plate of the gutter, thus preventing removal of the brace 1 after its foot has once been secured to the roof, until said foot is again released. When this is done, the lower end of the bracket may be swung upwardly, thus disposing the free end portion of the loop 8 parallel to the upright plate of the gutter, whereupon this loop may be moved downwardly and removed.

The device may be constructed of practically any preferred metal, but galvanized sheet metal is preferably provided on account of its weather proof qualities. Furthermore, the bracket may be varied in a number of ways falling within the scope of the following which I claim as my invention:

A roof gutter bracket comprising a substantially rectangular strip, one end being bent laterally to provide an attaching foot, its opposite end being bent into the form of an S, one loop of which is larger than the other, the smaller loop being disposed to one side of the plane of the body portion of the strip with its free end joined to the end of said body portion, the larger loop being disposed to the opposite side of said plane with its free end extended, the last named loop being adapted to receive the free edge of the gutter bead, while its curved portion abuts the adjacent surface of the straight portion of the gutter, the extended end being disposed within the gutter bead.

In testimony whereof I have hereunto set my hand in presence of two subscribing witnesses.

HUGO BOLDT.
